DOOR RACK

Joseph Usoskin, New York, N. Y.

Application April 16, 1943, Serial No. 483,247

2 Claims. (Cl. 211—41)

This invention relates to a new and improved door rack construction for kitchen cabinets or the like.

The principal object of the invention is to provide an improved rack construction for kitchen cabinet doors, having novel and improved means for holding dishes in the compartments of the door against rattling when the door is opened or closed.

Another object of the invention is to provide a door rack having improved adjustable means for adjustably retaining articles on the door.

Another object of the invention is to provide a novel adjustable rack for doors for kitchen cabinets or the like, which will safely and effectively hold dishes and the like in the compartments of the rack or doors.

Another object of the invention is to provide an improved rack for holding articles which may be secured to a door as a complete unit, or which may form part of the door, that is, the door forming the rear wall of the rack.

Numerous additional objects of the invention will be stated in the annexed description and drawing which illustrate preferred embodiments thereof.

Fig. 1 is a partial front elevational view of the improved adjustable rack, constructed and arranged in accordance with the invention, the dishes held by the said rack being indicated in broken lines.

Fig. 2 is a sectional view on the line 2—2 of Fig. 1.

Fig. 3 is a sectional view on the line 3—3 of Fig. 1.

Fig. 4 is a view similar to Fig. 2 but showing a different form of guide slot.

The improved rack comprises a pair of side walls 9 and 10, a rear wall 11, and a plurality of shelves or partitions 12 which divide the rack into a number of compartments. These compartments 17 may be of equal or unequal size.

Side walls 9 and 10 are identical in all respects, and are assembled in vertical parallel relation. Said side walls may be connected to rear wall 11 or may be integral therewith. The said side walls may be directly secured to the door of a kitchen cabinet or the like when the door is to serve as the rear wall of the rack structure.

As is clearly illustrated in Fig. 2, each of said side walls 9 and 10 is provided with a series of aligned vertical slots 13. Each of slots 13 has a series of horizontal extensions, in this case, three, identified by the references 13a, 13b, and 13c, respectively. 13a is the upper horizontal slot, 13c the lower slot and 13b is the intermediate slot. Each compartment 17 contains a complete slot unit, comprising slots 13, 13a, 13b and 13c, in each of side walls 9 and 10. In other words, there is provided a complete slot unit in each of side walls 9 and 10 intermediate each pair of partitions 12. Each slot unit is identical in all respects and has the appearance and contour of the letter E in reverse. Slots 13, 13a, 13b and 13c in side walls 9 and 10 are aligned for cooperation with each other.

As shown in Fig. 2, slot 13b is equi-distant from slots 13a and 13c. It will be noted that the distance between slot 13a and the nearest partition 12 is greater than the distance between slot 13c and the nearest partition 12.

The rack structure is provided with a plurality of bars or retaining rods 14 which extend transversely of the rack and are normally parallel to the door or rear wall 11. Each of said bars 14 has reduced ends 14a, which are adapted to extend through slots 13, 13a, 13b and 13c. Each of reduced ends 14a of bars 14 are provided with the external threads 14b. These reduced ends 14a of the respective bars 14 are clamped or locked in position in the vertical slots 13 or the horizontal slots 13a, 13b and 13c by means of the wing nut or ordinary thumb screws 15.

The reduced ends 14a of bars 14 can be moved vertically in the respective vertical slots, and said reduced ends of each bar can also be moved horizontally in any pair of selected horizontal extensions 13a, 13b and 13c of the respective vertical slots 13. The reduced ends 14a of each holding or retaining bar 14 can thus be moved vertically and horizontally in order to hold the dish or plate P firmly in place. I have shown a pair of rods 14 to be employed with each compartment 17 but only one holding bar may be employed if desired.

The principal novelty of the invention resides in the provision of the horizontal slot extensions 13a, 13b and 13c of the vertical slots 13. By means of this construction, the holding bars 14 may be adjusted to properly accommodate and securely hold plates, dishes and objects of varying sizes and shapes. If a low guard is desired to hold the article in compartment 17, then holding bars 14 are clamped in horizontal slots 13b and 13c, as shown in compartment A of Fig. 1. If a higher guard is desired, then bars 14 are moved into slots 13a and 13b, as shown in compartment B of Fig. 1.

The embodiment illustrated in Fig. 4 is substantially identical to the embodiment just de-

scribed and illustrated in Figs. 1 to 3, save that the slots in side walls 9 and 10 are different in contour than slot units 13. As will be noted from Fig. 4, slot 16 has the general shape of the letter S. In this alternate form, bars 14 can likewise be adjusted to accommodate plates and objects of varying sizes and shapes.

As shown in Fig. 3, the rack may be secured to any door D as a separate unit, or as heretofore stated, the door itself may form the rear wall of the rack structure.

I have shown and described preferred embodiments of my invention, but it is obvious that numerous changes and omissions can be made without departing from its spirit.

I claim:

1. A rack device for doors and the like comprising side walls and a rear wall and a plurality of partitions dividing the same into a series of compartments, the side walls being provided with a plurality of vertical slots, each of said vertical slots being provided with a series of horizontal extensions, retaining rods extending transversely of the rear wall and connecting the side walls, said retaining rods having reduced ends which are located in the slots formed in said side walls, said

reduced ends of said retaining rods being movable vertically in the respective vertical slots and being also movable horizontally in any of the horizontal extensions formed in the side walls, and clamping means for holding the retaining rods in adjusted position.

2. A rack device for doors and the like comprising side walls and a rear wall and a plurality of partitions dividing the same into a series of compartments, the side walls of each compartment being provided with aligned vertical slots, each of said vertical slots being provided with a series of aligned horizontal slot extensions, movable adjustable retaining rods parallel to the rear wall and connecting the side walls, said retaining

15 rods having reduced ends which are adapted to extend through the slots formed in said side walls, said reduced ends of said retaining rods being movable vertically in the respective vertical slots and being also movable horizontally in any of the horizontal slot extensions formed in the side walls, and clamping means for holding the reduced ends of the retaining rods in position in the vertical or horizontal slots.
